UNITED STATES PATENT OFFICE.

GARNET W. COEN, OF SAN FRANCISCO, CALIFORNIA.

OIL BURNER.

Application filed September 28, 1921. Serial No. 503,727.

To all whom it may concern:

Be it known that I, GARNET W. COEN, a citizen of the United States, residing at the city and county of San Francisco and State of California, have invented new and useful Improvements in Oil Burners, of which the following is a specification.

This invention relates to oil burners, and especially to means for obtaining thorough atomization of the oil and a uniform homogeneous mixture of the oil and the atomizing medium employed.

Some fuel oil burners in use today, employing air or steam, have one serious fault, that is, being unable to maintain a homogeneous mixture of the oil and the atomizing medium. Stratification of the atomized mixture before leaving the burner nozzle often occurs, causing a fire which may be heavy near the edges and conversely entirely too light at the center. Thorough atomization of the oil, particularly during load changes when the fires are increased or decreased, is almost unobtainable and numerous other difficulties might be mentioned.

One of the objects of the present invention is to generally improve and simplify burners of the character described, and especially to provide a burner in which stratification of the oil and atomizing medium will be avoided and a uniform flame obtained; further a burner in which uniform mixing of the oil and steam will take place, and in which thorough atomization can be relied upon during all load charges.

Further objects will hereinafter appear.

The invention consists of the parts and the construction, combination and arrangement of parts as hereinafter more fully described and claimed, having reference to the accompanying drawings, in which—

Fig. 1 is a side elevation of the burner partially in section.

Fig. 2 is an end view of the burner nozzle.

Fig. 3 is a side elevation of the atomizing and mixing member employed.

Fig. 4 is a front view of the member shown in Fig. 3.

Referring to the drawings in detail, A indicates a fitting. On this fitting are three threaded extensions as indicated at 2, 3 and 4. Connected with the extension 2 is an oil delivery pipe not shown, and mounted interior of the extension 2 is a strainer 5. Con-

nected with the extension 3 is a steam inlet pipe not shown, and connected with the extension 4, by means of a union coupling 6, is a sleeve 7 in which is secured a burner pipe 8. Secured on the outer end of the pipe 8 is a burner tip or nozzle 9, on the outer end of which is formed an elongated slot 10, and extending through the pipe 8 and the extension 4 of the housing A is a pipe 11 to which oil is delivered by means of a passage 12 which forms a communication between the strainer and the inner end of the pipe. Secured on the outer end of the pipe 11 is a combined atomizing and mixing member B, and adapted to regulate the flow of oil and steam are valves of suitable construction which in this instance are not shown.

The combined mixing and atomizing member is disposed within the nozzle or burner tip 9 and is secured to the outer end of pipe 11 by any suitable means or as here shown by a threaded connection 13. The member is substantially cylindrical in shape and is provided with angularly disposed vanes 14 at one end and longitudinally disposed or straight vanes 15 at the opposite end.

The interior of the burner tip 9 is provided with a cylindrical chamber 16 which is drilled out or otherwise machined to form a fairly finished surface. The ends of the vanes 14 and 15 are similarly turned to form a fit between the interior of the tip 9 and the vanes. It can therefore be seen that a central chamber 17, hereinafter to be termed a mixing chamber, is formed between the vanes 14 and 15 and the burner tip. The inner end of the member B is cored out or drilled to form a central chamber 18. One end of this chamber is threaded to receive the threaded end 13 of the pipe 11, while the other end of the chamber merely forms a pocket into which the oil of pipe 11 discharges. Four or more radially disposed holes 19, of fairly small diameter, form a communication between the pocket 18 and the annular mixing chamber 17 and it is therefore obvious that the oil delivered by the pipe 11 will discharge through these openings.

In actual operation it is obvious that the oil delivered through the extension 2 will first pass through the strainer 5, the passage

12 and pipe 11 before it finally enters the pocket 18 and discharges through the radially disposed openings 19. Similarly that steam admitted through the extension 3 will 5 flow through the passage indicated at 20 and then through an annular passage 21 formed between the burner pipe 8 and the oil pipe 11, finally entering the annular mixing chamber 17 by passing through the openings 10 22 formed between the interspaced angularly disposed vanes 14. A swirling movement is in this manner imparted to the steam as it enters the mixing chamber 17 and a thorough mixing of the steam and oil is obtained. 15 Atomizing of the oil, however, takes place previous to the mixing action as the openings 19 through which the oil discharges are disposed directly in front of the interspaced openings 22 formed between the 20 vanes, that is the steam entering at high velocity through these openings will pass directly over the discharge ends of the openings 19, thus serving the function of jets which first causes an atomizing action, and 25 then a mixing action due to the swirling movement imparted. The oil when thoroughly atomized and mixed with the steam will next discharge between the longitudinally disposed vanes 15 and will then escape 30 through the elongated slot 10, and finally discharge into the furnace box or space where combustion takes place.

The provision of the vanes 15 is an important feature of the present invention as it 35 prevents stratification of the oil and steam within the burner tip or nozzle 9 before the mixture discharges, that is the swirling movement imparted by the vanes 14 sets up a rotary action which would cause the oil to 40 be thrown outwardly against the inner surface of the cylindrical portion of the tip 9, thus causing more of the mixture to pass through the ends of the slot 10 than in the center, the result being an uneven fire. This 45 condition, however, is entirely avoided when the vanes 15 are employed as the swirling movement and centrifugal action produced is broken up or counteracted by the vanes 50 15, and a jet-like discharge is obtained between these vanes. Stratification is thus avoided and a uniform homogeneous mixture is discharged through the slot 10 which insures a flame of even thickness and 55 temperature.

From the foregoing it can be seen, first, 60 that stratification is avoided and a uniform flame is obtained; second, thorough atomization is secured by placing the openings 19 directly in front of the spaces formed between the vanes 14; third, thorough mixing of the steam and oil is obtained by the swirling movement and it is thus obvious that 65 variations in load will have no effect either upon the atomizing or mixing action of the burner as these actions are affected not only

by the blast or jet action of the steam, but also by the mechanical action produced by the vanes 14 and 15.

While the mounting for the mixing and atomizing member here shown is more or less specifically illustrated, and similarly the connections therewith, I wish it understood that various changes in form and proportion may be resorted to within the scope of the appended claims, similarly that the materials and finish of the several parts employed may be such as the experience and judgment of the manufacturer may dictate or varying uses may demand.

Having thus described my invention, what I claim and desire to secure by Letters Patent is—

1. In a burner of the character described, a pair of pipes, one interior of the other, one for delivery of steam and the other oil, a combination atomizing and mixing member secured on the outer end of the oil delivery pipe, vanes on the exterior surface of said member and at each end thereof, and interspaced with relation to each other to form a mixing chamber, a plurality of radially disposed openings formed in the member communicating with the oil pipe and the mixing chamber, and a burner tip enclosing said member.

2. In a burner of the character described, a pair of pipes one interior of the other, one for the delivery of steam and the other oil, a combination atomizing and mixing member secured on the outer end of the oil delivery pipe, said member being substantially cylindrical in shape and elongated, a plurality of interspaced angularly disposed vanes formed on one end of the member, a plurality of longitudinally disposed vanes formed on the exterior surface and on the other end of said member, a burner tip enclosing the member and the vanes formed exterior thereof and engaging the outer ends of the vanes, means for securing the burner tip with relation to the steam delivery pipe, a mixing chamber formed between the angular and the longitudinally disposed vanes, and a plurality of radially disposed openings formed in the cylindrical member and communicating with the oil delivering pipe and the mixing chamber.

3. In a burner of the character described, a combination atomizing and mixing member, cylindrical in shape and having a central chamber formed therein connected with a source of oil supply, a plurality of angularly disposed vanes surrounding one end of the member, a plurality of longitudinally disposed vanes surrounding the other end of the member, said angular and longitudinal vanes being interspaced to form an annular mixing chamber, radially disposed oil discharging openings formed in the member communicating with the source of oil

supply and the annular mixing chamber, and a casing surrounding the member and the respective vanes formed thereon, said casing being connected with a source of steam supply.

4. In a burner of the character described, a combination atomizing and mixing member, cylindrical in shape and having a central chamber formed therein connected with a source of oil supply, a plurality of angularly disposed vanes surrounding one end of the member, a plurality of longitudinally disposed vanes surrounding the other end of the member, said angular and longitudinal vanes being interspaced to form an annular mixing chamber, radially disposed oil discharging openings formed in the member communicating with the source of oil supply and the annular mixing chamber, a casing surrounding the member and the respective vanes formed thereon, said casing being connected with a source of steam supply, a nozzle-like projection formed on the casing, forward of the combined atomizing and mixing member, and a contracted opening formed in said nozzle-like projection.

5. The combination with the burner tip and the steam and oil delivering pipes connected with the same, of a cylindrical chamber formed within the burner tip, a cylindrical member disposed within the burner tip and having a central chamber formed therein, means for securing said cylindrical member to the end of the oil delivering pipe, a plurality of angularly disposed interspaced vanes formed on one end of the cylindrical member, a plurality of longitudinally disposed interspaced vanes formed on the other end of the cylindrical member, said angular and longitudinal vanes being separated with relation to each other to form an annular mixing chamber between the burner nozzle, the cylindrical member

and the respective vanes, the exterior ends of the respective vanes snugly engaging the inner surface of the cylindrical chamber formed within the burner nozzle, a plurality of radially disposed oil discharging openings formed in the cylindrical member and communicating with the central chamber formed therein and with the annular mixing chamber, and an elongated contracted opening formed in the forward end of the burner tip.

6. In an oil burner, the combination with the burner tip and the steam and oil delivering pipes connected therewith, of means within the burner tip for imparting a swirling movement to the steam, an annular mixing chamber formed between said means and the burner tip into which the steam discharges with a swirling movement, means for projecting oil radially into the mixing chamber, and a plurality of longitudinally disposed vanes arranged in front of the mixing chamber to direct a mixture of steam and oil in a forward direction and to correct the swirling movement imparted to the steam and oil.

7. In a burner of the character described, a combined atomizing and mixing member comprising a cylindrical shaped elongated member, a plurality of interspaced angularly disposed vanes disposed exterior thereof and on one end, a plurality of interspaced straight vanes also formed on the exterior and on the opposite end, each set of vanes entirely surrounding the member, said member also having a central chamber formed therein and a plurality of radially disposed discharge passages communicating with the chamber, said passages terminating at their opposite ends at a point intermediate the angular vanes and the straight vanes.
